EXERCISER

Bertha Saunders, Los Angeles, Calif.

Application December 27, 1941, Serial No. 424,567

4 Claims. (Cl. 272—57)

This invention relates to an arcuate-reciprocal exercising device which has the general form of a turntable, the top surface or platform of which is flat, or substantially so, to receive the feet of a standing person. When the person standing upon the platform swings has or her body in hula hula fashion, the result is the awakening of lazy muscles about the legs, feet and waist as the turntable reciprocates in an arcuate motion. Such exercise of the waist of a person's body vitalizes muscles seldom used and hence is conducive to relieving strain fatigue and the improvement of body lines. Obviously, the exerciser conditions the abdominal muscles, stimulates the blood stream and normalizes the body functions in general.

One of the principal objects of the invention is to present an improved body exerciser which is simple and sturdy of construction and economical to manufacture.

A further object is to present a disc-like exerciser which is firm in balance and gives long care-free service.

Other objects, advantages and features of my invention will appear from the accompanying drawing, the subjoined detailed description, the preamble of these specifications and the appended claims.

Applicant is about to illustrate and describe one of the forms of her invention in order to teach one how to make, and use the same, but it is to be understood that the drawing and description thereof are not to limit the invention in any sense whatsoever, except as limited by the appended claims.

In the drawing:

Fig. 1 is a top perspective view of the invention.

Fig. 2 is a side elevation showing parts broken away and in section.

Fig. 3 is a perspective view of a part of the invention.

Fig. 4 is a perspective view of another part of the invention.

Fig. 5 is a perspective view of a modified form of a part of the invention.

The form of the invention shown in Figs. 1 to 4 has a base element 1 and a turntable element, rotatable plate, or platform 2, the base being supported from a floor or ground surface by a plurality of non-skid button-like elements 3 which may be rubber. The base and turntable elements may be plywood, plastics or any other suitable material.

The base has a central protrusion or boss portion 4 through which is a bore 5. This boss 4 extends into a hole or socket 6 of the plate 2. This socket has a shoulder which receives a large washer 7 through which passes the bolt 8. On the bottom of the base is a fibre washer 9 and beneath the slotted head of the bolt is an iron washer 10. A nut 11 is used so that the base and plate can be adjustably held together. A lock washer, not shown, may be used between the nut and washer 9. Between the plate and base are large fibre washers 12 and 13. The washer 12 may be held to the plate by wood screws and the washer 13 to the base by a hollow rivet 14". The hollow rivet provides an opening through which a lubricant, such as petroleum jelly, may be fed to lubricate the sliding surfaces of the fibre washers 12 and 13. Obviously, the base 1, elements 3, and the boss 4 are subjacent means of support for the rotatable plate 2 and so arranged that the plate will not noticeably tilt.

Fixed to the top of the base 1, are a plurality of spacer means runners or bearing blocks 14 spaced around the center or pivot boss 4. These blocks or flat bearing units 14 may be cemented to the base and have smooth top surfaces. The blocks are means to provide some friction and may be metal, but hard wood has proven very satisfactory. Instead of these blocks being located between the center boss 4 and the outer perimeter of the base, they may be placed close to the outer perimeter as shown at 14' in Fig. 5. In circular alignment with the row of blocks 14 is a hole 15, and a similar hole 15' in circular alignment with the blocks 14'. The purpose of the holes 15 and 15' is to provide an opening through which a lubricant, such as petroleum jelly may be placed upon the under side of the plate 2 so that the plate will easily run smoothly over the blocks.

The blocks 14 and 14' provide stability to the rotatable plate 2, thus preventing vertical play between the plate and base with the result that the person using the exerciser can maintain a proper poise. To avoid slipping between a person's feet and the plate, the plate is provided with a non-skid covering 16 which may be rubber having an annular flange 17 and a plurality of raised portions 18. The covering is preferably cemented to the top of plate 2. Beneath the hole 15, there is a door 19 pivoted at 20 and having a finger grip 21. This door has a vent hole 22 to avoid possible vacuum conditions that may exist between the plate and base.

Having thus described my invention, what is

claimed as new and desired to be secured by Letters Patent is:

1. An exercising device having an upper rotatable plate means and subjacent means of support therefor, pivot means at the center of the plate means and subjacent means, spacer means at the pivot means fixed to one of the aforementioned means intermediate the plate means and the subjacent means and radially spaced from the pivot means, and a plurality of bearing blocks spaced apart in a circular row intermediate the center and perimeter of the device to provide friction and stability to the device.

2. The device recited in claim 1 wherein the plate means is provided with a non-skid covering having depending flanges which terminate below the top surface of the subjacent means.

3. An exercising device having a disc-like form with short resilient feet to support it on a floor, said device comprising a base element and a rotatable plate element, fixed spacer means at the center of the elements and between them, said means being spaced from and surrounding the center of said elements, means at the center of the elements to pivot them together, and friction means intermediate the spacer means and the perimeter of the device to provide stability for the plate element.

4. The device recited in claim 3 wherein the friction means are flat units and form a track at the outer perimeter of the device.

BERTHA SAUNDERS.
